Specification for Design.

Patented Mar. 12, 1918.

Application filed December 21, 1917. Serial No. 208,326. Term of patent 7 years.

To all whom it may concern:

Be it known that I, JOHN L. FLANNERY, Jr., a citizen of the United States, residing at Chicago, county of Cook, and State of Illinois, have invented a new, original, and ornamental Design for a Display Card or Label, of which the following is a specification, reference being had to the accompanying drawing, forming a part hereof.

The figure is a plan view of a display card or label in accordance with the design.

Changes not altering the essential appearance may be made without departure from the invention.

I claim:

The ornamental design for a display card or label as shown and described.

JOHN L. FLANNERY, JR.
